UNITED STATES PATENT OFFICE

HENRY W. GRAVES, OF CHICAGO, ILLINOIS

METAL STRUCTURAL TOY

Application filed May 28, 1928. Serial No. 280,972.

My invention relates to the general class of structural toys consisting of connectors adapted for interchangeably connecting rods or strips, so that structures of widely varying types and sizes can be erected from such elements.

Generally speaking, the objects of my invention are those of providing simple and inexpensive metal elements for this purpose which will interlock firmly without requiring any auxiliary fastening elements, which can instantly be interlocked or released even by a child and without the use of any tools, which will permit relatively flat assemblies of the elements, and which will require small space for packing them.

In my copending application No. 222,650 entitled Structural toys and filed September 24, 1927, I have shown structural toy elements comprising strips each having slotted ends bent out of the general plane of the strip, and connectors each formed for interlocking with strip ends projecting through perforations in the connector. In practice, the structural toy of that application has shown these objections: The forming of bent parts upon both the strips and the connectors increases the cost, the bends on the strips greatly increase the space required for packing the latter, and the strips must be of fairly heavy metal to retain their bends at the desired angle.

My present invention aims to overcome all of these shortcomings by providing a connector and strip combination in which no bends are required in the strips, thereby permitting these to be flat, thin, and compactly packed; and also by providing a connector and strip combination in which each strip engages the connector face from which the projections on the connector extend, thereby producing a more nearly flat assembly in which the connections are not so conspicuous.

Still further and also more detailed objects will appear from the following specification and from the accompanying drawings, in which

Fig. 1 is an elevation of a connector and of a single strip interlocked with it, showing

an embodiment in which the companion hook members on the connector are disposed in alinement.

Fig. 2 is an enlarged and fragmentary side elevation, taken from the right hand side of Fig. 1.

Fig. 3 is a similarly enlarged and fragmentary section taken along the line 3—3 of Fig. 2.

Fig. 4 is a fragmentary view of a strip and connector assembly in which the companion hook members on the connector are parallel to each other.

Fig. 5 is a fragmentary view taken from the bottom of Fig. 4.

Fig. 6 is a fragmentary elevation of a connector and strip end assembly, showing an embodiment in which the companion latching elements on the connector are parallel to each other and perforated to receive projections on the strip end.

Fig. 7 is a section along the line 7—7 of Fig. 6.

Fig. 8 is a view similar to a portion of Fig. 4, but showing the companion hook elements as bowed toward each other.

Fig. 9 is a fragmentary perspective view showing portions of a connector and strip formed as in Figs. 1 to 3, but with the strip end bent at right angles to the main portion of the strip.

In the embodiment of Figs. 1 to 4 inclusive my structural toy comprises flat strips 1 blanked from resilient steel or other metal, with medial longitudinal slots 2 extending into each strip from opposite ends of the strip to divide each strip end into laterally spaced arms 3.

The arms 3 at each end of the strip have opposed outwardly opening edge recesses 4 adapted to be entered respectively by the shanks of the hereafter described hook elements. Each such recess is preferably of a depth slightly less than half the width of the slot 2 between these arms and desirably slightly less than half of the slot width, so that the arms can be flexed toward each other to decrease the effective width of the strip end by a distance at least equal to the joint depth of the said opposed recesses.

and each slot is of sufficient length to permit the arms of the corresponding strip end to be flexed toward each other for laterally contracting the strip end to that extent.

To connect such strips in various formations, I provide connectors formed of flat sheet metal and provided with pairs of spaced latching fingers or hook elements, these pairs of hook elements being counter-
parts of each other in formation and spacing, and each pair being adapted to interlock with a notched end portion of one of the strips. Thus, Fig. 1 shows a connector comprising two generally flat webs 5 and 6 disposed at right angles to each other, each web having a plurality of pairs of hook elements radiating from a point at or near the juncture of that web to the companion web. Each hook element has a basal shank 7 of a thickness substantially equal (or slightly less) than the length of one of the strip edge recesses 4, and the shanks 7 of each pair of hook elements project at right angles to the web from which they are formed, with a clear spacing between them corresponding to the normal distance between the bottoms of the opposed recesses on the strips, it being understood that the strip ends are all counterparts regardless of variations in the lengths of the strips.
Each hook element also has a head or hooking portion 8 projecting toward the companion hook element and presenting a shoulder spaced from the adjacent face of the connector web by a distance substantially equal to the uniform thickness of the strips.

With the connectors and strips thus formed, any strip end can readily be slipped into the latched position shown in Figs. 1 and 3 by first digitally contracting this end, after which the resiliency of the strip spreads its end arms so that the hooks 8 of the adjacent hook elements overhang opposite sides of the strip and hold the latter flatwise against the adjacent connector web, while the spreading of the arms causes the oppositely directed recesses 4 to be entered by the shanks 7 of the hook elements to prevent a longitudinal sliding of the strip upon the contiguous connector web. Such a connecting may be effected by sliding the digitally contracted strip end flatwise along the connector face, as for example toward the left in Fig. 1 from the right hand edge of the web 5, and I desirably taper the outer tip edges of the strip arms 3 toward each other (as shown in Figs. 1 to 3) to facilitate this. However, the attaching may also be done by first slipping the uncontracted strip end in laterally tilted position between opposed connector fingers, as shown in dotted lines in Fig. 2, and then contracting the strip end digitally while snapping it down into its latched position, thus facil-

tating the interlocking of such strips with rigidly spaced connectors.

Since the attached strip end has portions underhanging each of the hooks 8 of the adjacent pair of hook elements, and since these hooks have their inward or hooking faces spaced from the adjacent face of the connector by a distance corresponding substantially to the thickness of the strip end, the latter is effectively clamped against the connector, and the entry of the recesses 4 by the inner portions of the shanks 7 latches the strip against longitudinal sliding.

Hence the resulting connection is quite strong and positive, and also is not materially affected by slight variations in the dimensions of the parts, such as the ordinary variation in the exact thickness of the strip stock. Moreover, the strips can be manufactured quite cheaply in any desired lengths with the same tools, while the connectors are also cheaply blanked and formed from sheet metal.

By using connectors having two webs at right angles to each other, with the pairs of hook elements on each web tangential of a single circle, I enable the user to erect structures with the strips disposed at a wide variety of angles. I may attain this variety also by employing single web connectors in connection with both flat strips (such as that of Fig. 1) and strips with end portions bent at right angles to the main part of the strip after the manner shown in Fig. 9.

However, while I have heretofore described an embodiment in which the companion hook elements are in alinement, I do not wish to be limited to this, since other arrangements may also be employed without departing either from the spirit of my invention or from the appended claims. For example, Figs. 4 and 5 show an embodiment in which the hook elements of each pair are parallel to each other and have their shanks 9 in flatwise engagement with the bottoms of the edge recesses 10 in the arms 3 of the adjacent strip end. In this case, each recess corresponds in length to the width of one of the shanks 9, and the hooks 11 desirably project longitudinally of the strip in both directions beyond the said shanks, as shown in Fig. 5. Furthermore, these hooks might be bowed toward each other (as shown at 11A in Fig. 8) to increase the extent to which they overhang the adjacent strip arms.

So also, I do not wish to be limited to having the recess portions of the interengaging formations on the strips, as these might be on the connectors. Thus, Figs. 6 and 7 show portions of an embodiment in which each strip has oppositely directed nubs 12 projecting from its slot-spaced arms 3, and in which the latching elements on the connector web 5 comprises two parallel wings

13 spaced by the normal width and the strip end and each having a perforation entered by one of the said nubs 12.

With each of the illustrated embodiments, the connectors can be made of a cheap grade of stiff metal, while an inexpensive grade of steel suffices for the strips, and the latching elements on the connectors can be of such small height as not to be conspicuous in the erected structures.

10 I claim as my invention:

1. A structural toy comprising single piece strips formed of flat resilient metal having counterpart resilient and laterally contractible flat end portions, and single piece connectors each having a flat portion and a plurality of integral pairs of latching elements projecting in the same direction at right angles to the face of the said flat connector portion, the latching elements of each pair being spaced and formed for interlocking with opposite edge parts of an interposed strip end portion and for retaining the strip end portion closely adjacent to the 25 said flat connector portion.

2. A structural toy comprising strips having counterpart flat and longitudinally slotted end portions each provided with opposite edge recesses, and connectors having flat portions each provided with pairs of hook elements projecting in the same direction from a face thereof, each pair of hook elements comprising shanks spaced for respectively entering the opposite edge recesses on one strip-end portion and hook heads extending toward each other beyond the shanks, the hook heads being spaced from the said connector face by substantially the thickness of one of the strip-end 40 portions.

3. A structural toy comprising flat strips having counterpart longitudinally slotted end portions each provided with opposite edge recesses, and connectors having flat portions each provided with pairs of hook elements projecting in the same direction from a face thereof, each pair of hook elements being formed from the adjacent flat portion of the connector and shaped both 45 for extending into one of the strip edge recesses and for overhanging the strip to clamp the latter against the said flat connector portion.

4. A structural toy comprising resilient strips having counterpart ends, and connectors each having a plurality of latching means for interlocking with one of the strip ends; each strip being longitudinally slotted from each end and provided near each end with oppositely directed edge recesses of a depth less than half the width of one of the said slots; each of the latching means comprising a pair of fingers bent from the connector in the same direction away from a 60 face of the connector and spaced by a dis-

tance substantially equal to the width between the opposed recess bottoms in a strip end, each such finger having a widened head spaced from the said face by a distance substantially corresponding to the thickness 70 of a strip and disposed for overhanging a strip end interposed between the two fingers.

5. A structural toy comprising resilient strips having counterpart ends, and connectors each having a plurality of latching means for interlocking with one of the strip ends; each strip being longitudinally slotted from each end and provided near each end with two oppositely disposed and outwardly open edge recesses of a depth less than half the width of one of the said slots; each of the latching means comprising a pair of fingers bent from the connector in the same direction away from a face of the 80 connector and spaced by a distance substantially equal to the distance between the bottoms of the two oppositely disposed recesses in a strip end; each such finger having an edge portion adapted to enter one 85 of the recesses in a strip end interposed between that finger and the companion finger of the same pair, each finger also having a head adapted to overhang such interposed strip end and spaced from the said 90 connector face by a distance substantially corresponding to the thickness of a strip.

6. A structural toy member formed of sheet metal and having a plurality of pairs of freely spaced hooks projecting at right 100 angles to a flat face portion of the said member, the hooks of each pair directed toward each other and having their hooking faces disposed at a common distance from the said flat face, the hooks of each 105 pair being flat and substantially in alignment, the several pairs of hooks projecting from the flat face portion being disposed with the flat faces of each pair in alignment and at equal distances from a common center and at right angles to radii from that common center.

7. A structural toy comprising single piece strips of resilient metal having counterpart flat and laterally contractible end portions, and connectors; each formed of a single piece of sheet metal, each connector having a flat portion and a plurality of counterpart pairs of hook elements projecting in the same direction at right angles 115 to the face of the said flat portion; each hook element having a portion spaced from the said face and disposed for overhanging a strip end portion interposed between this hook element and the companion hook element of the same pair so as to hold the interposed strip end portion against the face of the flat connector portion from which the two hook elements project, the two hook elements of each pair having opposed edge 120 125 130

portions formed for interlocking with the strip end portion interposed between them to prevent longitudinal movement of the strip having the said interposed end portions.

- 5 8. A structural toy comprising single piece sheet metal connectors having counterpart formations and flat single-piece resilient metal strips having counterpart ends; each such strip having each end thereof longitudinally slotted to make it laterally contractible, and having each end portion provided with opposed lateral edge formations spaced from its tip; each of the said 10 counterpart formations on a connector comprising a pair of projections spaced to permit a strip end to be inserted edgewise between them when the strip end is laterally contracted, the projections being formed 15 both for interlocking with the opposed edge formations on the interposed strip end and for retaining the strip end flatwise closely adjacent to the portion of the connector adjacent to the projections.
